Primary Examiner — Bridget L Eland*Assistant Examiner* — Lauren McVey(74) *Attorney, Agent, or Firm* — Rutan & Tucker, LLP**(57) CLAIM**

The ornamental design for a needle guide, as shown and described.

DESCRIPTION

FIG. 1 is a top perspective view of a needle guide;
 FIG. 2 is a bottom perspective view thereof;
 FIG. 3 is a first side elevation view thereof;
 FIG. 4 is a front elevation view thereof;
 FIG. 5 is a second side elevation view thereof;
 FIG. 6 is a top plan view thereof;
 FIG. 7 is a rear elevation view thereof; and,
 FIG. 8 is a bottom plan view thereof.
 The broken are directed to environment; the broken lines form no part of the claimed design.
